GESELLSCHAFT, OF SIEMENSSTADT, NEAR BERLIN, GERMANY

AUTOMATIC TELEPHONE SYSTEM

Application filed August 5, 1929, Serial No. 383,522, and in Germany September 3, 1928.

The present invention relates to a circuit arrangement for telephone systems, in which one lead of a subscriber's line is used for special purposes (signal repeating, feeding from the main exchange battery two subscribers of a P. B. X.).

The object of the invention is to control, in a particularly simple and reliable manner, the connecting devices of the exchange by means of the circuit changes brought about by the subscribers' stations for setting up or completing a connection. This is achieved in that a switching means is brought into action over one lead of the subscriber's line by circuit changes brought about by the subscribers' stations for setting up or completing a connection, and the said switching means controls the switching devices at the connecting devices of the exchange over the part of the second lead that is not used for the particular purposes.

In the drawings are shown several methods of carrying out the invention. Thus, Fig. 1 shows an arrangement for telephone systems with call seekers, group selectors, and final selectors, in which subscribers' stations N1 and N2 communicating with one another are fed from the main exchange battery over: earth, battery, choking coil D4, lead b, choking coil D6, and thence on the one hand over choking coil D7, subscriber's loop for N1, choking coil D8 to earth, and on the other hand over choke coil D9, subscriber's loop for N2, choking coil D10 to earth.

Fig. 2 shows a system with preselectors, group selectors, and final selectors, in which over one lead of the subscriber's line for N3 are transmitted the signals for any particular purpose (alarm signal).

Fig. 3 shows another arrangement of the switching means which is brought into action over one lead of the subscriber's line and effects certain switching operations over the other lead, and in this case only the disconnection of ringing current is effected when the subscriber's station answers an incoming call.

The rectangles enclosing the windings of various relays shown on the drawings indicate that these relays are made slow-acting

by the addition of a copper slug on the core of the relay or in any other well-known manner.

If the main station N of a private branch exchange shown in Fig. 1 wishes to set up a connection with some subscriber of the main exchange; and for that purpose takes down his receiver, the relay A is energized over one lead, namely lead a in this case, in the following circuit: earth, choking coil D2, subscriber's loop of the main station N, lead a, relay A, contact 1t, resistance Wi, battery, earth. The closing of contact 2a causes the starting impulse given over the lead a to be transmitted over the lead b, relay T being energized over: earth, battery, choking coil D5, contact 2a, contact 3t, winding I of relay T, earth. The energizing of winding I of T only causes the contacts 4t and 5t to be closed. Contact 4t establishes the following circuit for relay R: earth, contacts 4t, 30p, 6t, relay R, battery, earth. Over contact 6r the rotary magnet DM receives impulses over: earth, relay interrupter RU, contacts 6r, 7p, rotary magnet DM, battery, earth. Hence, the wipers of the call seeker AS are moved on until they reach the calling subscriber's line, whereupon the following circuit is established over the wiper c1 of the call seeker AS: earth, contact 8r, windings II and I of relay P, wiper c1 of the call seeker AS, contact 5t, winding II of relay T, battery, earth. In this circuit is energized the relay P and the current flowing over the winding II of relay T causes the contacts 1t, 3t, and 6t to be opened. By opening the contact 7p, the relay P arrests the rotary magnet DM. At the contacts 10p and 126p the line is switched through and the impulse relay A1 is energized over winding I in the circuit: earth, choking coil D2, subscriber's loop of the main station N, lead a, relay A, wiper a1 of the call seeker AS, contact 126p, winding I of relay A1, battery, earth; while winding II of relay A1 is energized over:

earth, winding II of relay A1, contact 10p, wiper b1 of the call seeker AS, contact 2a, choke coil D5, battery, earth.

Contact 11p establishes the following circuit: earth, off-normal contact 12k, winding I of relay C, contact 11p, battery, earth. Re-

lay C is operated and locks itself over both its windings and contact 13c as soon as the off-normal contact 12k is opened at the first lifting step of the group selector. The short circuit is removed from relay C by contact 14a1, because, as previously mentioned, the relay A1 was energized after the call seeker had been positioned on the subscriber's line. The positioning of another call seeker on the subscriber's line is prevented by the removal of winding II of the relay P from the circuit of relays P and T. There is now the following circuit for the relays P and T: earth, contacts 9p, 125c, winding I of relay P, wiper c1 of the call seeker AS, contact 5t, winding II of relay T, battery, earth.

When the subscriber N transmits the first impulse train, the relay A1 is released in accordance with the interruptions at the impulse sender, the current being directly withdrawn from the winding I of relay A1 at the impulse sender, while that from winding II of relay A1 is withdrawn by contact 2a at each impulse, because the relay A, which lies in the circuit of winding I of relay A1 is also released at each impulse. In accordance with the impulse train, the lifting magnet HM receives impulses over: earth, contacts 15a1, 16c, shaft contact 17w, winding I of relay V, lifting magnet HM, battery, earth. The wipers of the group selector GW are raised to the corresponding level. During this impulse train the relay V remains energized because its windings II and III are short-circuited, making the relay slow-to-release. It falls back at the end of the impulse train and by closing the contact 18v the rotary magnet DM1 of the group selector GW receives current over: earth, contact 19p1, contact 18v, off-normal contact 20k, rotary magnet DM1, battery, earth. The wipers of the group selector take one rotary step and shaft contact 17w is opened. The contact 21dm1 is closed when the rotary magnet DM1 is energized; hence, relay V is again energized over: earth, contact 21dm1, windings II and I of relay V, lifting magnet HM, battery, earth. The lifting magnet is not energized in this circuit owing to the resistance of the relay V. Relay V opens its contact 18v, so that the circuit of the rotary magnet DM1 is opened and thus the contact 21dm1 is also opened. Relay V is again de-energized, so that the contact 18v is closed and the rotary magnet DM1 is again operated over the before-mentioned circuit and it moves on one step further the wipers of the group selector GW. This inter-action between the relay V and rotary magnet continues until the group selector has found a free final selector LW, whereupon the relays P1 and C1 are energized over: earth, contacts 22c, 23a1, windings II and I of relay P1, wiper c2 of the group selector GW, shaft contact 24w, winding II of relay C1, battery, earth. The open-

ing of contact 19p1 interrupts the circuit of the rotary magnet DM1, so that it cannot be energized again. The winding II of relay P1 is short circuited by the closing of contact 25p1, hence no other group selector can set itself onto the seized final selector LW. The relay V is deenergized when the group selector has been set onto the final selector. The line is switched through to the switch LW over the back contacts 26v and 27v and the front contacts 28p1 and 29p1. 75

When the group selector GW has tested, the relay C1 is energized as already mentioned and closes contact 31c1. The relay C1 locks itself over both its windings as soon as the final selectors LW has opened shaft contact 24w. 80

When the subscriber transmits a further train of impulses, the relay A1 of the group selector GW is released in accordance with the interruptions at the subscriber's station in the manner already described, and relay A2 of the final selector is energized by contact 33a1 over: earth, contacts 32c, 33a1, 29p1, wiper a2 of the group selector GW, windings I and II of relay A2, battery, earth. The lifting magnet HM and relay V at the group selector GW are not affected by the release of the relay A1, which closes the contact 15a1, because the lifting magnet HM is connected in series with the three windings of relay V, the proportions being such that they cannot thus be operated. 90

The energizing of relay A2 at the final selector LW causes the lifting magnet HM1 and the relay V1 to receive current over: earth, contact 34a2, winding I of relay V1, contact 35u, shaft contact 36w, lifting magnet HM1, battery, earth. The final selector LW is now raised to the level corresponding to the interruptions at the subscriber's station. The relay V1 is energized during this impulse train, because each time the relay A2 falls back the contact 37a2 is closed and so short circuits winding II of relay V1, thus rendering the relay slow acting, and it only releases its armature when the relay A2 has been released for some time, that is to say at the end of the impulse train. Thereupon the relay U is energized over: earth, off-normal contact 38k closed at the first lifting step, contacts 39v1, 40c1, winding I of relay U, shaft contact 36w, lifting magnet HM1, battery, earth. The lifting magnet HM1 is not operated in this circuit. On being operated, the relay U opens contact 35u and closes contact 41u. 105

The next train of impulses transmitted by the subscriber N now operate the rotary magnet DM2 over contact 34a2 in the circuit: earth, contact 34a2, winding I of relay V1, contact 41u, contact 42p2, rotary magnet DM2, battery, earth. The final selector LW is positioned onto the wanted line by the last impulse train, during which the relay V1 110 125 130

is maintained energized. During this time the relay U is locked up over: earth, contacts 43c1, 44u, 45v1, winding II of relay U, battery, earth. When relay V1 falls back at the end of the impulse train, the contact 45v1 is opened and contact 46v1 is closed. Although its locking circuit is thereby opened, the relay U does not fall back, because it is slow to release and over earth, contacts 43c1, 44u, 45v1, winding II of relay U, battery, earth, it again receives current owing to winding III of relay V1 being energized when the circuit for relay P2 is established in the manner to be described later.

It will be assumed that the wanted subscriber's line is arranged in the same manner as the main station N shown in Fig. 1. If it be free, the relay P2 is energized over contacts 43c1, 44u, 46v1, windings II and I of relay P2, wiper c4 of the final selector LW, winding II of relay T of the wanted party's call seeker, battery, earth.

Relay P2 is operated and by closing contact 47p2 it short circuits winding II of relay P2, thus preventing another final selector being set on the seized subscriber's line. Switching through at the final selector LW is effected at the contacts 52p2 and 53p2. Furthermore, contact 42p2 is opened and contact 48p2 is closed. Relay V1 receives energizing impulses from the relay interrupter RU1 over: earth, relay interrupter RU1, contact 49u, winding III of relay V1, contact 50y, contact 48p2, rotary magnet DM2, battery, earth. The rotary magnet DM2 is not operated over this circuit; but the closing of contact 45v1 causes the relay U to again receive current over its locking circuit as previously mentioned (earth, contacts 43c1, 44u, 45v1, winding II of relay U, battery, earth). Being slow acting, relay U does not follow the interruptions of relay V1. Contact 51v1 sends ringing impulses from the ringing machine RM to the lead a.

When the wanted station answers by taking down the receiver, the switching means A also for this station is energized over one lead, namely over: earth, choking coil D2, subscriber's loop of the wanted station, relay A, lead a3, wiper a4 of the final selector LW, contacts 52p2, 54v1, winding II of relay A2, battery, earth. Relay A of the wanted station is operated and closes the contact corresponding to contact 2a, thereby disconnecting ringing current, because the relay Y at the final selector LW is energized over: earth, battery, choking coil D5, contact 2a of the wanted station, lead b3, wiper b4 of the final selector, contact 53p2, relay Y, earth. By opening contact 50y, the relay Y interrupts the circuit of relay V1.

In this case likewise over the one lead (lead a) an impulse is sent for effecting a switching operation and it is passed on over the other lead, thus the impulse for disconnecting ring-

ing current, sent over one lead, is sent on over the other lead.

At the end of the conversation, when the calling subscriber hangs up the receiver, the relays A and A1 fall back owing to the interruption at the subscriber's station. On being short circuited over contact 14a1, the relay C releases its contacts, so that its own circuit is opened at contact 13c and at contact 12c is opened the circuit of relays P and T. Contact 124c short circuits relay P1, which falls back and at contact 25p1 opens the circuit of relay C1, while at contact 19p1 it again closes the circuit of the rotary magnet DM1. The latter is energized and moves the wipers of the group selector GW on one step, while over contact 21dm1 it energizes the relay V. The rotary magnet DM1 and relay V interact until the group selector GW reaches its extreme rotary position, from which it is mechanically restored to its normal position, opening contact 20k and thereby opening the circuit of the rotary magnet DM1.

The opening of the circuit of relay C1 at contact 31c1 prevents the relay C1 being again energized and so prevents the final selector LW being again seized during the releasing operation, because the shaft contact 24w is also open until the wipers of the final selector LW have reached their normal position. Furthermore, after relay P2 has been released owing to the opening of the contact 43c1, the following circuit is established for the rotary magnet DM2 of the final selector: 100 earth, off-normal contact 123k, contacts 122v1, 121c1, 120u, 42p2, rotary magnet DM2, battery, earth. On being energized, the rotary magnet DM2 moves the wipers of the final selector LW one step further and by closing contact 117dm2 it energizes the relay U over: earth, contacts 119u, 118c1, 117dm2, winding II of relay U, battery, earth. The latter at contact 119u opens its own circuit and at contact 120u that of the rotary magnet DM2. As relay U is slow to release, there is time for the circuit of the rotary magnet DM2 to be opened. But it is then again energized over the before-described circuit and causes the final selector arms to be moved on and the relay U to be energized. This action is repeated until the final selector LW has reached its extreme rotary position from which it is mechanically restored to normal, whereupon the off-normal contact 123k is 115 opened and the circuit of rotary magnet DM2 cannot be again established.

The setting up of a connection between the subscriber N3 in Fig. 2 and another subscriber will now be described.

The subscriber's line is so arranged that signals can be sent over one lead. The signal transmission is effected in the following manner. At or near the instrument of the subscriber N3 there is a key X associated with 130

the signalling device: the key is pressed when a signal is to be transmitted. It can be used for giving a fire alarm, etc. On pressing the key X, the following circuit is established 5 for the relay AR: earth, key α , relay AR, relay interrupter RU2, battery, earth.

Relay AR is energized by each impulse and by closing contact 55ar, it establishes the following circuit for the relay S: earth, contact 10 tact 55ar, choking coil D20, lead b5, choking coil D21, relay S, battery, earth. Relay S is energized in the same manner as relay AR, and the lamp L is flashed by the opening and closing of contact 56s. The lamp L is located at an alarm receiving position, which takes the necessary steps in known manner.

If the subscriber N3 wishes to make a call to a similar subscriber and for that purpose takes down his receiver, the relay A3 is energized in the following circuit: earth, choking coil D22, subscriber's loop of the station N3, lead a5, relay A3, battery, earth. This initial impulse received over the lead a5 is transmitted over the lead b by the closing of contact 25 tact 57a3, because thereby the relay R1 of the preselector VW is energized over: earth, relay R1, contact 58t2, contact 57a3, choking coil D23, battery, earth. Relay R1 is operated and at contact 59r1 closes the circuit of the 30 rotary magnet DM3 over: earth, relay interrupter RU3, rotary magnet DM3, contact 60t2, contact 59r1, wiper d7 of the preselector VW in the normal position, battery, earth. The preselected VW is thereby positioned 35 onto a free group selector GW.

When a free group selector GW1 has been found, the following circuit is established: earth, off-normal contact 61k, contacts 62v2, 63b, wiper c7 of the preselector VW, windings I and II of relay T2, contact 59r1, segment 1-10, wiper d7 of preselector VW, battery, earth. The relay T2 is operated and by opening the contacts 58t2 and 64t2 and closing the contacts 65t2 and 66t2, it switches 40 through the line and operates the relays A4 and B over the following circuits: (1) earth, battery, relay A4, wiper a7 of preselector VW, contact 65t2, lead a5, loop of the subscriber's station N3, choking coil D22, earth; 45 and (2) earth, contact 67a4, winding II of relay B, wiper b7 of preselector VW, contact 66t2, contact 57a3, choking coil D23, battery, earth. The opening of contact 67a4 removes the short circuit from winding I of relay B, 50 which is thus maintained energized over both windings.

The opening of contact 63b removes the short circuit from relay C2, which is operated and by closing contact 68c2 establishes 55 a circuit for the relays C2 and T2, which is independent of the contact 62v2 and off-normal contact 61k.

When the subscriber transmits the first impulse train, the relay A4 is released at each 60 impulse in the before-described circuit. The

relay A3 associated with the subscriber's line and the relay B controlled thereby are not affected by the interruptions at the subscriber's station, because they are slow in falling back. Relay A4 establishes the following circuit for the lifting magnet HM2 of group selector GW1: earth, contacts 69a4, 70c2, winding II of relay V2, contacts 77dm4, 72w, lifting magnet HM2, battery, earth. The group selector GW1 is raised to the wanted level 70 in accordance with the interruptions at the subscriber's instrument. Relay V2 only falls back at the end of the impulse train, because it is short circuited by contact 71a4 at each impulse of the train and thereby is rendered slow acting. On falling back at the end of the impulse train relay V2 at its contact 75v2 establishes the following circuit for the rotary magnet DM4: earth, contact 73p3, off-normal contact 74k which is closed at the first 75 lifting step, contact 75v2, rotary magnet DM4, battery, earth. The rotary magnet DM4 is operated and causes the wipers of the group selector GW1 to move on one step. At the same time the operation of the rotary magnet DM4 causes the contact 77dm4 to be opened and contact 76dm4 to be closed, thus establishing the following circuit for the relay V2: earth, contact 76dm4, winding I of relay V2, lifting magnet HM2, battery, earth. The lifting magnet HM2 is not operated in this circuit. The opening of contact 75v2 interrupts the circuit of the rotary magnet DM4. Hence, contact 76dm4 is opened and contact 77dm4 is closed. The opening of the shaft contact 72w at the first rotary step prevents the relay V2 being rendered slow acting when contact 77dm4 is closed. Relay V2 is deenergized and contact 75v2 returns to its normal position and the wipers of the group selector GW1 advance another step. This inter-action between relay V2 and the rotary magnet DM4 continues until the group selector GW1 has found a free final selector LW1. Thereupon the following circuit is 100 established: earth, contacts 78c2, 79a4, windings II and I of relay P3, wiper c8 of group selector GW1, off-normal contact 80k of final selector LW1, winding II of relay C3, battery, earth. Relays P3 and C3 are operated. Contact 73p3 opens the circuit of the rotary magnet DM4, while the closing of contact 81p3 short circuits the winding II of relay P3 thus marking the final selector LW1 105 engaged to other group selectors. The closing of the contacts 82p3 and 83p3 switches the lines through.

When the subscriber transmits the next impulse train, the relay A5 is energized each time the relay A4 falls back at the group selector GW1, the circuit extending over: earth, contact 84c2, 85a4, 83p3, wiper a8 of the group selector GW1, windings I and II of relay A5, battery, earth. The lifting magnet HM3 therefore receives impulses over: 110

earth, contact 86a5, winding I of relay V3, contact 87u1, shaft contact 88w, lifting magnet HM3, battery, earth. Thereby the final selector is set onto the wanted level.

The relay V3 located in the circuit of the lifting magnet HM3 is maintained energized during the impulse train because each time relay A5 falls back the winding II of relay V3 is short circuited at contact 89a5, thereby rendering the relay V3 slow to release. The relay V3 having fallen back at the end of the impulse train, the following circuit is established for the relay U1: earth, off-normal contact 90k, contacts 91v3, 92c3, winding I of relay U1, shaft contact 88w, lifting magnet HM3, battery, earth. The lifting magnet HM3 is not operated in this circuit. On being operated, the relay U1 opens the contact 87u1 and closes the contact 93u1.

When the subscriber transmits the last impulse train, the relay A5 is operated in accordance with the interruptions at the subscriber's station as before described, and thereby the rotary magnet DM5 is operated over: earth, contact 86a5, winding I of relay V3, contact 93u1, contact 94p4, rotary magnet DM5, battery, earth. During this impulse train likewise the relay V3 remains operated; and the relay U1 is maintained energized over: earth, contacts 95c3, 96u1, 97v3, winding II of relay U1, battery, earth; because the circuit of winding I of relay U1 is opened at the shaft contact 88w when the first rotary step has been taken. Testing takes place when the relay V3 falls back at the end of the impulse train. The relay U1 being slow acting it remains operated until the relay V3 is again operated by its winding III after testing has been effected. The circuit for the test relay P4 extends over: earth, contacts 95c3, 96u1, 98v3, windings II and I of relay P4, wiper c9 of the final selector LW1, lead c10, wiper c of the preselector of the wanted line, windings I and II of relay T at the pre-selector, wiper d, battery, earth. Relay P4 at the final selector LW1 is operated and by closing the contacts 99p4 and 100p4 it effects the switching through at the final selector.

Furthermore, contacts 94p4 is opened and contact 101p4 is closed, while contact 102p4 short circuits the winding II of relay P4, thus preventing any other final selector being positioned on the subscriber's line.

It is assumed, as previously mentioned, that the wanted station is arranged in the same manner as the calling station shown in Fig. 2. Relay V3 is energized by impulses over: earth, relay interrupter RU4, contact 103u1, winding III of relay V3, contacts 104y1, 101p4, rotary magnet DM5, battery, earth, but the rotary magnet DM5 is not operated. Relay U1 now receives current over: earth, contacts 95c3, 96u1, 97v3, winding II of relay U1, battery, earth. Relay U1 being slow to release it does not fall back when relay V3

is being energized by impulses. The relay V3 being operated at certain intervals, ringing current is sent from the ringing machine RM to the wanted station by the opening of contact 105v3 and the closing of contact 106v3.

When the wanted subscriber answers, the relay A3 belonging to his line is energized over: earth, battery, relay A3, subscriber's loop of the wanted station, choking coil D22, 75 earth. On the relay A3 of the wanted station being operated over the lead a it operates over the lead b the relay Y1 at the final selector LW1 by closing the corresponding contact a3, the circuit extending over: earth, battery, choking coil D23, contact 57a3, lead b10, wiper b9 of the final selector LW1 contact 99p4, relay Y1, earth. Relay Y1 is operated and by opening the contact 104y1 it interrupts the circuit of the relay V3. Thus, 85 no more ringing current is sent out. Relay U1 also falls back, because relay V3 is no more energized. The subscribers are now interconnected.

At the end of the conversation, when the calling subscriber N3 hangs up his receiver, the relay A3 of his line is released and by opening the contact 57a3 it releases the relay B at the group selector GW1. Relay B short circuits the relay C2 at contact 63b, 95 hence relay C2 also returns its contacts to normal. At contact 107c2, the relay C2 short circuits the relay P3, which falls back and again energizes the rotary magnet DM4 over: earth, contact 73p2, off-normal contact 74k, contact 75v2, rotary magnet DM4, battery, earth; hence the wipers of the groups selector GW1 advance one step. At the same time the contact 76dm4 is closed by the rotary magnet DM4, hence the relay V2 is energized 105 over: earth, contact 76dm4, winding I of relay V2, lifting magnet HM2, battery, earth; but the lifting magnet HM2 is not operated in this case. Relay V2 opens the contact 75v2, thereby interrupting the circuit of the rotary magnet DM4. The contact 76dm4 is also opened again, hence the contact 75v2 returns to the normal position. Thereupon the rotary magnet DM4 again receives current over the before-mentioned circuit. This is repeated until the group selector GW1 leaves the last contact of the row and the wipers of the switch are mechanically returned to the normal position. The off-normal contact 74k is then opened so that DM4 cannot be 115 energized again.

When the relay C2 was short circuited by contact 63b as previously mentioned, it fell back and its contact 107c2 short circuited the relay P3, which also fell back. Thereby the circuit of relay C3 was opened and it returned its contacts to the normal position, so that the rotary magnet DM5 is energized over: earth, off-normal contact 110k, contacts 111v3, 112c3, 113u1, 94p4, rotary magnet DM5, 125 130

battery, earth; and the wipers of the final selector are advanced a step.

When the rotary magnet DM5 is operated, the relay U1 is energized over earth, contacts 5 114u1, 115c3, 116dm5, winding II of relay U1, battery, earth. On being operated, relay U1 at contact 113u1 opens the circuit of the rotary magnet DM5 and at contact 114u1 it opens its own circuit, hence relay U1 falls 10 back again and the before-described circuit of the rotary magnet DM5 is closed again, so that the wipers of the final selector are advanced one step further. This continues until the switch has left the last contact in 15 the row and the final selector is then returned to the normal position by mechanical power in known manner.

Fig. 3 (at the bottom of Fig. 1) shows a further arrangement of the switching means 20 A belonging to the connecting up point and arranged to cut off the ringing current; it receives the initial impulse over one lead and sends it on over the other lead. In this modification, when the subscriber answers an 25 incoming call, the relay A is energized over the lead a, and the initial impulse thereby given for disconnecting the ringing current is sent on over the other lead b at contact a to operate the ring-cut off relay, such as Y1 of Fig. 30 2. In this case, the switching means A lies in the part of the subscriber's line coming from the final selector and the initiation of a call over the subscriber's line operates the T relay of the preselector directly. 35 Now, in order to prevent the switching means A and A3, associated with the subscriber's line in Figs. 3 and 2, respectively, being affected during the transmission of ringing current in the case of incoming calls, 40 they are rendered slow to operate.

What is claimed is:

1. In a telephone system wherein a portion of one conductor of a line extending to a subscriber's station is used for special purposes, means at said station for transmitting signals over the other conductor of said line, and means for repeating said signals over a part of the first conductor not being used for special purposes.
- 45 2. In a telephone system, a substation, a line extending to said substation comprising two conductors, a portion of the first of said conductors being used for special purposes, means at said substation for transmitting impulses over the second of said conductors to set up a telephone connection, and means for repeating said impulses over a portion of said first conductor not being used for special purposes in order to assist in the establishment of 50 the connection.
- 55 3. In a telephone system, a line outgoing from a subscriber's station, means for extending said line to a line relay, means including a calling device at said station for 60 intermittently energizing one winding of said

relay over one conductor of said line, a second relay in said conductor energized in series with said winding, a second winding on said line relay, and means responsive to the operation of said second relay for energizing 70 said second winding over the other conductor of said line.

4. In a telephone system wherein one portion of one conductor of a line extending to a subscriber's station is being used for special purposes, said portion being insulated from the remainder of the conductor by condensers, a line relay having two windings, means at 75 said station for transmitting signals over the second conductor of said line to the first winding of said line relay, and a relay in series with said first winding for repeating said signals to the second winding of said line relay over a portion of the first conductor not being used for special purposes.

5. In a telephone system, a subscriber's station, a line extending to said station comprising two conductors, a portion of the first of said conductors being used for special purposes and being insulated from the remainder 90 of the conductor by condensers, a connector having access to said line, means in said connector for transmitting ringing current over the second conductor of said line, a relay in said second conductor responsive to the removal of the receiver at said substation, and means controlled by said relay over a portion of the first conductor not being used for special purposes for disconnecting said ringing current.

6. In combination, a line comprising two conductors, a line relay having two windings, a second relay in series with one conductor of said line, the first winding of said line relay, and a battery, and contacts on said second relay for closing a circuit for the second winding of said line relay over the other conductor of said line.

7. In combination, a line relay having two windings, a second relay in series with the first winding of said line relay, means for transmitting impulses to said second relay and the first winding of said line relay, and means controlled by said second relay for repeating said impulses to the second winding of said line relay.

8. In a telephone system wherein a portion of one conductor of a line extending to a subscriber's station is used for special purposes, a connector having access to said line, means in said connector for transmitting signalling current over the second conductor of said line, and means responsive to the removal of the receiver at said station for effecting the disconnection of ringing current over a portion of said first conductor not being used for special purposes.

9. In a telephone system wherein a portion of one conductor of a line extending to a subscriber's station is used for special pur-

poses, a line finder having access to said line, means responsive to the initiation of a call at said station for transmitting an impulse over the second conductor of said line, and

5 means for repeating said impulse over a portion of the first conductor not being used for special purposes to effect the starting of said line finder.

10. In a telephone system, a subscriber's line, a line finder having access thereto, a start relay in said finder, means responsive to the initiation of a call over said line for transmitting a starting impulse over one conductor of said line, means for repeating said impulse over the other conductor of said line, and means responsive to the repeated impulse for energizing said start relay.

11. In a telephone system, a subscriber's station, a line extending from said station to an exchange, condensers connected in series in one conductor of said line whereby a section thereof is isolated from the remainder of the conductor to be used for special purposes, means for completing telephone 25 connections to and from said line, and means for supplying talking battery to said station from said exchange.

12. In a telephone system, a subscriber's station, a line extending from said station to an exchange, condensers connected in series in one conductor of said line whereby a section thereof is isolated from the remainder of the conductor to be used for special purposes, a line relay in said exchange having two windings, means for bridging said relay across said subscriber's line in series with a battery, and means including a calling device to said subscriber's station for controlling said line relay to establish a telephone 40 connection.

In witness whereof, I hereunto subscribe my name this 9th day of July, A. D. 1929.

MAX LANGER.
